UNITED STATES PATENT OFFICE

RICHARD SAXON BEDE, OF HARPURSVILLE, NEW YORK

CHIMNEY-SCAFFOLD BRACKET

Application filed December 10, 1928. Serial No. 325,025.

My present invention has reference to an adjustable staging or scaffolding for pitch or gable roofs and is primarily directed to the supporting brackets for such scaffoldings.

5 The primary object of the invention is the provision of extremely simple but strong and durable brackets which may be arranged and sustained upon a roof without the employment of nails or analogous devices, and 10 which will effectively support thereon the scaffold boards for the masons and material employed in building or repairing chimneys.

A further object is the provision of a device for this purpose which while strong and 15 durable shall be light in construction and which may be readily folded to provide a small package that can be conveniently carried from building to building or stored in a small space when not required for use.

20 A still further object is to provide a scaffold bracket for pitch roofs which shall comprise two members designed each to rest and to be supported on the opposite sides of a pitch roof, easily and quickly adjustable with 25 respect to the roof, and readily separable whereby one of the brackets, or rather one pair of brackets may be employed independently of the other.

The invention will be fully and comprehensively understood from a consideration of 30 the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as 35 do not affect the spirit of the invention nor exceed the scope thereof as expressed in the appended claims.

In the drawings:

Figure 1 is an elevation of a roof of a building illustrating the application of my improvement thereon.

Figure 2 is a top plan view thereof.

Figure 3 is a detail sectional view approximately on the line 3-3 of Figure 2.

50 Figure 4 is a sectional view approximately

on the line 4-4 of Figure 1 looking in the direction of the arrows.

Figure 5 is a plan view of one of the cam levers employed.

Figure 6 is a perspective view of one of the 55 yokes employed.

Figure 7 is a perspective view of one of the scaffold supporting members.

Figure 8 is a similar view of one of the roof 60 engaging members.

Figure 9 is a sectional view approximately on the line 9-9 of Figure 3.

Figure 10 is a sectional view approximately on the line 10-10 of Figure 8.

Figure 11 is a side elevation of the device 65 when in folded condition.

In the showing of the drawings my improved scaffold brackets are illustrated as arranged in connected pairs upon the angle sides of the roof of a building 1. It will be 70 apparent, however, as the description progresses that a single pair of these brackets upon one of the angle sides of the roof may be employed.

Each bracket constitutes a roof engaging 75 member in the nature of a board or plate 2. On its under face each of the plates 2 has fixed thereto transversely arranged metal strips which I will term cleats and which are designated by the numeral 3 in the drawings. The cleats 3 are arranged respectively at the 80 center and at the ends of the plate 2 and project beyond the edges of the said plate. The projecting ends of the cleats have openings 4 therethrough for the reception of nails or like securing elements when it is necessary to nail the plates 2 on the roof. In this connection it should be stated that when the device is arranged as illustrated by the drawings no 85 nails or other securing elements are required and that the cleats 3 serve as friction means 90 for contacting with the opposite sides of the roof.

Each plate 2, adjacent to its outer end has riveted or otherwise secured thereto a plate 95 having upwardly directed angle arms 5 provided with alining openings 6, and each of the said plates 2 in a line with its edges and at its opposite end has secured thereon longitudinally extending plates 7 that merge into 100

upwardly and outwardly directed flat eye portions 8. The eyes 8 receive therethrough removable pivots 9. The pivots 9 pass through the depending arms 10 of substantially U-shaped members which underly and provide rests for the plates 11. Resting on the plates 11 are the confronting ends of the scaffold supporting plates or boards 12, and disposed over the confronting ends of the said scaffold boards there are longitudinal plates 13 disposed opposite the plates 11. Passing through the plates 13, the scaffold supporting boards or members 12, through the plates 11 and the U-shaped members, which carry the arms 10 there are bolts 14 which are engaged by nuts.

Arranged between the upstanding elements 5 on the plates 2 there are the rack members 16 of the improvement. Preferably each of the racks comprises a board that has secured to its edges metal plates 17, and these plates have their inner edges provided with alining notches 18. The plates 17 have passed therethrough removable pivots 19 that also pass through the openings 6 in the elements 5.

Secured on the edges of the scaffold or staging supporting members 12 and extending beyond the outer ends thereof there are plates 20. Connecting each pair of plates 20 there is a pair of spaced rods 21 and 22, the rods 21 being disposed in close proximity to the outer ends of the scaffold or staging supporting members 12. The rack members are designed to be received between the extensions or plates 20 and there are pivoted on the rods 22 the cam ends 23 of levers 24. The body of each lever is substantially U-shaped, as disclosed by Figure 5 of the drawings, and the said body is centrally formed with a stem 26 which is threaded. By swinging the levers to bring their cam faces 23 against the notched members or racks 16 the latter will be swung toward the members 12 so that the rods 21 will be received in one pair of the notches 18 in the said members 16.

Received in one pair of notches in each of the members 16 there is a continuous member or yoke 27 provided at its outer end with an eye 28 through which the stem 26 passes, and there is threaded on the stem 26 for adjustable contact with the eye 28 a bolt 29. The staging boards supported upon the members 12 are indicated by the numeral 30. The members 12 are preferably of wood and if necessary the staging boards 30 may be nailed thereto. Under ordinary weather conditions, however, this is not necessary.

From the foregoing description when read in connection with the drawings it will be seen that I have produced a simply constructed, cheap, evenly balanced but efficient bracket for supporting scaffolding or like stagings which may be easily arranged on the roof, readily adjusted with respect to said roof and which is of a strength to support thereon the

masons and the material required by the masons in erecting or repairing a chimney in the building 1.

As previously stated, one pair of brackets instead of two pairs of connected brackets may be employed when the device is not to be used on the peak of the roof. In this instance, it is merely necessary to remove the nuts from certain of the bolts 14, and thus detach one member 12 from the other member 12. When one pair of the brackets are employed it will be necessary to drive nails or other securing elements through the openings 4 in the cleats 3.

When the device is not required for use the nut 29 is unscrewed from the shank 26 of the cam levers 24, permitting the yokes 27 to swing on the members 16, and likewise permitting the members 16 being brought out of engagement with the cam levers and with the rods 21 and thereafter swing over the plates 2 in a direction toward each other, as disclosed by Figure 11 of the drawings. By reference to this figure it will be seen that the device when folded or collapsed produces a small bundle which may be readily conveyed from one building to another and stored into a small space when the device is not in use.

Having described the invention, I claim:

1. A scaffold bracket for pitch roofs, comprising a plate to be laid on a roof, cleats arranged transversely on the under face of the plate and extending beyond the edges thereof and having openings, securing means to pass through the openings that enter the roof, a staging supporting member hingedly secured to the plate and having outer extensions, and a transverse rod connecting said extensions, a notched member pivotally secured to the plate and received between the mentioned extensions, a cam lever pivoted between the extensions and swingable to contact with the notched member to move the same to bring the rod into one of the notches thereof, and means for locking the cam lever on the notched member.

2. In a foldable scaffold bracket, roof engaging plates having cleats, arms pivoted to one end of the plates, right angular elements fixed on the ends of the arms, scaffold supporting members removably secured to said elements, plates secured to and extending beyond the outer ends of said members, a lever having cam ends which are pivoted to said last named plates, notched members pivotally secured to the roof plates, swingable to pass between the plates on the scaffold supporting members and to be engaged by the cams on the levers, a yoke engaging the notch in each of said members and the mentioned levers, and adjustable means on the levers engaging the yokes for holding said yokes on said levers.

In testimony whereof I affix my signature.

RICHARD SAXON BEDE.
